PRINTING OF CHARTS

Joseph Neumann and Rudolph Neumann,
New York, N. Y.

Application November 17, 1933, Serial No. 698,412

3 Claims. (Cl. 101—426)

The present invention relates to the printing of circular charts and it particularly relates to the printing of both sides of such charts for dial instruments.

5 The charts for the usual types of dial instruments for continuously measuring and recording temperature, pressure, carbon dioxide content and so forth over a considerable period of time are provided with a series of closely spaced circular 10 graduations, which must be most accurately centered upon the axis of the dial of the instrument and also be provided with a series of transverse curved graduations indicating the passage 15 of time, extending radially outwardly from the central portion of the chart.

Due to the high degree of accuracy required in centering these charts, so that their axes will exactly coincide with the axes of the dial and so that their transverse radial curved graduations 20 will cooperate accurately with the pivotal indicating and recording arm, it has been customary to graduate these charts on only one side, as it was not possible by methods hitherto employed to assure that graduations, if applied to both 25 sides of the chart, would be accurately centered upon the axis of the dial.

Among the objects of the present invention are to provide a method of forming and printing dial charts of the character above described, in which 30 it will be possible to print the charts on both sides with assurance that the graduations on both sides, will substantially coincide and will be substantially exactly centered upon the dial axis.

Other objects will appear during the course of 35 the following specification.

In accomplishing the above objects it has not been found possible to utilize the usual type of centering or aligning means employed in printing processes, in which the lower and one of the 40 side edges of the sheet of paper are brought up against and contacted with a series of stops or rules.

In order to assure accurate registration of the chart it has been found desirable to square the 45 chart with intersecting lines positioned around the exterior of the circular graduated portion, which crossing lines or corner lines must coincide when the chart is held up against the light. These crossing or corner lines serve as a guide 50 for the printer.

The above and other objects will appear more clearly from the following detailed description, when taken in connection with the accompanying drawing, which illustrates a preferred embodiment of the inventive idea.

In the drawing:

Figure 1 shows a circular chart after printing on both sides about one-quarter size, with the back of the chart partly turned over, and

Figure 2 shows the front of the chart.

Referring to Figs. 1 and 2, the charts are printed upon square sheets of paper 10 from plates, preferably with blue ink upon a white background.

These plates are prepared in the following manner. The chart is carefully plotted and made by an engineer after a determination of the characteristics of the instruments to which the dial chart is to be applied. This chart is then engraved on wax and the wax coating is coated with 65 graphite dust to make it electrically conductive. The coated wax engraving is then copper-plated by an electrolytic process and the thin sheet of copper is removed therefrom and backed up by 70 lead.

Then another wax impression is made from this backed-up sheet of copper, which wax impression is again coated with graphite and plated to make a reproduction which may be provided 75 with a hardened steel face.

This sheet is then screwed upon a wooden block and the center part thereof is removed and a circular knife is inserted for concentrically cutting out the center of the chart simultaneously upon printing the same. Assurance is thus had 85 that the center of the chart will be correctly positioned in regard to the circular graduation lines.

The plate is then placed in a printing press, preferably of the flat bed variety, and the plate 90 is applied to one side of a stack of sheets of paper 10, the center of the sheet being simultaneously cut out with the printing of the chart thereon. As previously stated, it has been found preferable to print blue lines on white, as a 95 much better reading is obtained upon such a chart, when the red ink of the indicating arm is applied thereto.

Referring to Figs. 1 and 2, the circular chart 100 lines 11 indicate the pressure or temperature or so forth, while the curved radial lines 12 indicate the passage of time. As stated before, the central portion of the chart 13 is cut out by the circular knife in the center of the plate 105 simultaneously with the printing of the chart thereto. It will be noted, as shown in Figs. 1 and 2, that the hours are indicated by the numerals 14, around the outer margin 15 of the chart, which outer margin is partly colored dark blue, as at 16, to indicate the night hours, and 110

partly uncolored at 17 to indicate the day hours.

The essential features of the present invention reside in the provision of the corners or crossing or meeting lines 18 symmetrically about the chart, the lines of which are tangent to the outer circles 11. It is by means of the provision of these lines 18 that it is possible to print the charts of Figs. 1 and 2 on both sides, an accomplishment not hitherto attainable.

- 10 In the printing operation, when the entire batch of sheets 10 have been printed on one side, the batch is then reversed and is run through on the reverse side. Ordinarily, the guide blocks 19 on the lower edge and on one of 15 the side edges would be sufficient for reverse printing, but in charts of the character described in the present application where a high degree of accuracy is necessary, these guide blocks 19 and 20 do not suffice to assure accurate printing.
- 20 The corners 18 enable the assurance of a very accurate registry on the front and back of the chart. The apparatus is first set so that the corners on the front and back of the charts when 25 printed will exactly coincide when the chart is held up to the light, and throughout the printing the guides 19 and 20 may be adjusted to achieve this registry. When this registry is made, assurance is had that there will be a very exact registry of the circular graduations on 30 both sides of the chart.

After the charts have been printed on both sides, they may be cut by a steel die to the circle 21, and this last cutting operation need not be extremely accurate since the charts have been 35 most accurately centered on both sides so that their graduations 11 will correspond in a predetermined manner.

When the charts are printed on both sides as in the present case it is very necessary to provide 40 special paper which will not shrink during the interval between operation of printing on one side and then on the other side. The best type of paper is that which contains at least 30% rag stock. The amount of rag preferably varies between 35% and 50%. The remainder of the 45 stock is principally sulphite pulp.

This paper should be highly calendered and should be deeply surfaced with a sizing to prevent penetration of moisture so that all fibers both on the surface and substantially below the 50 surface will be thoroughly coated with the sizing and will be altogether non-absorptive of the moisture or ink applied. The blue ink applied to this chart should be of an unfading base.

55 Paper so treated is highly non-absorptive and highly non-hygroscopic and in the finishing operations it is preferably loft-dried. It is obvious that many modifications may be made in the method set forth and the accompanying example is given by way of illustration and not by way of limitation.

60 By employing both sides of the charts for recording, it is possible to assure more economical storage since these charts are often kept for long

periods of time in the permanent archives of laboratories, manufacturing and public service corporations and so forth.

In Fig. 2 at the corner of the sheet indicated by the numeral 30 is shown a slightly different means of alignment which may be utilized in addition to or in lieu of the corners 18. Although shown at only one corner 30 it may be also placed at the four corners of the sheet of Fig. 2. As indicated, this modified alignment consists of two parallel arcs 31 and 32 outside of the line 21, through which arcs pass the radial diagonal lines 33.

What is claimed is:

1. A method of printing both sides of circular charts having a plurality of relatively closely spaced circular graduations on both sides, the registry of which cannot be readily determined by looking through the chart when held up to the light, said charts being particularly designed for dial recording instruments said method being for the purpose of assuring that said circular graduations shall substantially exactly register which comprises forming on said charts a series of spaced right angle corners at intervals of 90° and positioned substantially to the outside of the circular graduations, which corners are made of lines tangent to the outer circular graduations, the printer in printing said charts on the reverse side making certain said corners are in exact registry on the front and back of the chart by holding the chart up to the light during the printing operation.

2. A method of printing circular charts having a plurality of relatively closely spaced circular graduations on both sides, the registry of which cannot be readily determined by looking through the chart when held up to the light, said charts being particularly designed for dial recording instruments said method being to assure that the circular graduations shall substantially exactly register, which comprises providing a printing plate having a central knife to cut a central opening and a plurality of corners around said chart, which corners are caused to register exactly when the chart is printed on both sides.

3. A process of printing circular charts designed for dial recording instruments on both sides, said charts to be provided with a plurality of relatively closely spaced circular graduations, the registry of which cannot be determined by holding the chart up to the light and looking therethrough, said process being to assure that the circular graduations shall substantially exactly register, which comprises forming on said charts at spaced 90° intervals a radial line and two crossing concentric circular lines positioned substantially to the outside of the outermost of the circular graduations, the printer in printing said charts on the reverse side making certain said corners are in exact registry during printing by holding the chart up to the light during the printing operation.
